UNITED STATES PATENT OFFICE.

JOSEPH M. WHITE, OF DANVILLE, ILLINOIS.

DESIGN FOR AN AUTOMOBILE-FOOTBOARD.

55,494.

Specification for Design. Patented June 15, 1920.

Application filed May 28, 1919. Serial No. 300,495. Term of patent 7 years.

To all whom it may concern:

Be it known that I, JOSEPH M. WHITE, a citizen of the United States, residing at Danville, in the county of Vermilion and State of Illinois, have invented a new, original, and ornamental Design for an Automobile-Footboard, of which the following is a specification, reference being had to the accompanying drawing, forming part thereof.

Figure 1 is a plan view of an automobile foot board, showing my design.

Fig. 2 is a section therethrough.

I claim:

The ornamental design for an automobile footboard, as shown.

JOSEPH M. WHITE.
